[57] **CLAIM**

The ornamental design for a two-handed controller for video games and simulations, as shown and described.

DESCRIPTION

FIG. 1 is a top, rear, left perspective view of a two-handed controller for video games and simulations, showing our new design;

FIG. 2 is a bottom, front, left perspective view thereof;

FIG. 3 is a top plan view thereof;

FIG. 4 is a bottom plan view thereof;

FIG. 5 is a rear elevational view thereof;

FIG. 6 is a front elevational view thereof;

FIG. 7 is a left side, elevational view thereof showing a data transmission cable; and,

FIG. 8 is a right side, elevational view thereof, showing a data transmission cable.

The broken line showing of data transmission cable in FIGS. 7 and 8 is for illustrative purpose only and forms no part of the claim.
